UNITED STATES PATENT OFFICE.

FRED EDWARD FANGER, OF MEXICO, MEXICO.

ATTACHMENT FOR TYPEWRITERS.

Application filed October 7, 1925. Serial No. 60,972.

My invention relates to typewriter attachments, whereby the user of the typewriter may know at any time how many lines may be still written upon the unused portion of the paper in the machine.

The object of the present invention is to effect an improvement on the construction disclosed in my prior Patents No. 1,477,048, issued December 11, 1923, and No. 1,507,278, 10 issued September 2, 1924.

One of the objects of the invention is to effect an improvement in the construction of the indicating drum. Instead of the drum being made of a single piece, it now 15 consists of two pieces including a ring encircling the drum proper, on which ring the scale is stamped or affixed. Inside of the drum there is a flat spring, instead of a spiral spring, as shown in my prior patents, 20 this flat spring holding the ring in proper position, but permitting the ring to be revolved around the drum proper.

A further object of the invention is to provide an alarm bell that will sound whenever the ring on the drum has reached a certain point, signalling to the typist that the predetermined point in the work sheet has been reached.

With these and other objects in view, my 30 invention consists of certain novel and peculiar features of construction and combination of parts, as hereinafter described and claimed, and in order that it may be clearly understood reference is to be had to the accompanying drawing, in which—

Fig. 1 is a longitudinal section of the attachment applied to a Remington machine;

Fig. 2 is a section on the line 2—2 of Fig. 40 1;

Fig. 3 is an elevation of the indicating drum; and

Fig. 4 is an elevation showing the bell operating mechanism.

Referring more particularly to the drawing, 1 is the platen of a Remington machine. The attachment is secured to the machine by means of the arm 2 having the split sleeve 3 which fits over the stationary part 4 on the machine and which can be 50 securely fastened thereto by setting up the screw 5 to draw the two parts of the split sleeve together.

The attachment is mounted to rotate on an extension 6 of the axle of the platen, the said extension being provided with the cus-

tomary knurled head 37. Rigidly secured at one end of the arm 2 is a stud shaft 8 carrying a pinion 9 adapted to rotate thereon. At the extreme upper end of the arm 60 2 is a pointer 10 secured thereto by a screw 11, which permits angular adjustment of the said pointer. At the lower end of the arm 2 is a shaft 12 having a bell 13 secured thereto.

Rotatably mounted on the axle 6 is the drum 7 provided at the rim with gear teeth 14 which are adapted to mesh with the pinion 9. Between the teeth 14 and the side wall 15 of the drum is interposed the leaf 70 spring 16, comprising a circular portion 17, and an offset portion 18, the ends 19 and 20 being normally adjacent each other. Connecting the teeth 14 and the side wall 15 is a thin web portion 15', which has a cut-away section 21 and a smaller cutaway section 22 diametrically opposite thereto.

Rotatably mounted on the drum 7 is the ring 23 which carries the indicating scale on its circumference. The leaf spring 16 being 80 normally under compression, the portions 17 and 18, respectively, protrude through the cutaway portions 21 and 22 and thereby frictionally engage the inner surface of the ring 23, normally holding the drum and ring non-rotatable with respect to each other, but permitting rotation when sufficient force is applied to the ring to overcome the said resistance. Shoulders 24 and 25 secured to the inner side of the drum 90 lock the ring and drum in assembled position.

Secured to the inner edge of the ring 23 is a lug 26 for engaging the tapper arm 27 to ring the alarm. The tapper arm is 95 bent from wire to provide a projection 28 for engagement with the lug 26, the wire then being coiled around the shaft 12 to provide a spring. For locking the tapper arm so as not to ring the bell, a lever 29 is 100 rotatably mounted on the shaft 12 having a handle 30 and an angular arm 31 which engages the tapper arm 27 to hold it down in inoperative position. A spring finger 32 is adapted to engage notches 33 in the arm 2 to frictionally lock the lever 29 in set position. The said lever is also provided with an arm 34 for limiting the rotary movement of said lever by engagement with the lower end of the arm 2.

When it is desired to set the indicating ring at the beginning of the typing of a

sheet, it is merely necessary to turn the said ring with such pressure as to overcome the frictional resistance as differentiated from my prior invention, wherein the whole ⁵ drum must be moved axially and only after disengagement of the internal gears and pinions could it be rotated to the desired position.

I claim:—

- 10 1. A typewriter attachment comprising a rotary drum, a ring provided with indicia normally rotatable with the drum, a leaf spring interposed between the ring and drum and in frictional engagement with one ¹⁵ of them.
2. A typewriter attachment comprising a rotary drum, a ring provided with indicia surrounding the drum, a leaf spring carried by the drum, cutaway portions on the drum, ²⁰ the said spring projecting through the cutaway portions and in frictional engagement with the ring.

3. A typewriter attachment including a support adapted to be secured to a fixed part of a typewriter adjacent the axle of the ²⁵ platen roller, a rotatable pinion mounted on said support, a drum rotatably mounted relative to said axle and provided with gear teeth for co-operating with said pinion, a ring provided with indicia mounted to ³⁰ normally rotate in unison with said drum, means for permitting manual rotation of said ring relative to said drum, means for preventing movement of said ring axially of the drum, an alarm bell carried by said support and comprising a tapper, means carried by the ring for engaging the tapper to operate the bell at a predetermined point, and means for locking the tapper to prevent ³⁵ the bell from ringing at said point. ⁴⁰

In testimony whereof I affix my signature.

FRED EDWARD FANGER.
